CLAIM

The ornamental design for a playmat for a baby, as shown and described.

DESCRIPTION

FIG. 1 is a perspective view of a playmat for a baby, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top plan view thereof, shown in an alternate configuration with the playmat for a baby in an unfolded position; and,

FIG. 9 is a perspective view thereof, shown in an alternate configuration with the playmat for a baby in a partially unfolded position.
